US00D629210S

(12) United States Design Patent
Hong

(10) Patent No.: US D629,210 S
(45) Date of Patent: * Dec. 21, 2010

(54) TEXTILE FABRIC

(76) Inventor: Jongchul Hong, 275 Wembley Cir.,
Atlanta, GA (US) 30328

D489,904 S * 5/2004 Lee D5/30
D514,332 S * 2/2006 Mariani D5/20
D578,885 S * 10/2008 Ban et al. D9/434

() Term: 14 Years

* cited by examiner

(21) Appl. No.: 29/316,568

Primary Examiner—Robert M Spear

Assistant Examiner—Barbara B Lohr

(74) Attorney, Agent, or Firm—Harry I. Leon

(22) Filed: Oct. 8, 2009

(57) CLAIM

(51) LOC (9) Cl. 05-02

The ornamental design for a textile fabric, as shown and described.

(52) U.S. Cl. D5/30; D5/59

(58) Field of Classification Search D5/4,
